UNITED STATES PATENT OFFICE.

RICHARD FRIEDRICH WOLFFENSTEIN, OF BERLIN, GERMANY, ASSIGNOR TO P. BEIERS-DORF & COMPANY, OF HAMBURG, GERMANY.

PROCESS FOR THE MANUFACTURE OF SOAPS CONTAINING PEROXIDS.

No. 917,828.

Specification of Letters Patent.

Patented April 13, 1909.

Application filed August 13, 1908. Serial No. 448,421.

To all whom it may concern:

Be it known that I, RICHARD FRIEDRICH WOLFFENSTEIN, subject of Germany, residing at Berlin, Germany, have invented new and useful Improvements in Processes for the Manufacture of Soaps Containing Peroxids, of which the following is a specification.

It has been sought to manufacture soaps containing active oxygen, as such soaps are of great value for disinfecting as well as for bleaching purposes. The hitherto known soaps of this kind are however mere mechanical mixtures of common soaps with peroxidized alkaline compounds, such as sodium peroxid, percarbonate of sodium, perborate of sodium, and therefore suffer from all those disadvantages inherent in a mere mixture of different combinations, since the combination lacks the desired uniformity and such preparations also tend more easily to decomposition. Furthermore the soaps thus produced are excessively alkaline, on account of the alkali of the peroxid compound being added to that already present in the soap itself.

It has been found that it is possible to obtain non-alkaline soap preparations containing oxygen as peroxid, by bringing together the alkali salts of the per-acids, for instance the percarbonate of sodium or perborate of sodium with the free fatty acids. It is very remarkable, and contrary to what would have been expected, that the salts of the said per-acids are so stable that they can be used

in this manner instead of the caustic alkalis or alkaline carbonates.

For manufacturing the soap preparations in question, the free fatty acids commonly used for the manufacture of soap, such as 40 palmitic acid, stearic acid, oleic acid or mixtures of same are caused to act upon the alkali combinations of peracids such as perborate of sodium, the free fatty acid being caused to act in molecular proportion for 45 about quarter of an hour upon the peroxid salt of sodium at the temperature of the water bath until the desired reaction has taken place. A little water may be added if desired. The termination of the reaction is 50 easily recognized when it is found that the common organic solvents no longer extract the fatty acids, showing that the formation of the desired sodium salts has taken place.

Having now particularly described and 55 ascertained the nature of the said invention and in what manner the same is to be performed, I declare that what I claim is:

In the method of manufacturing soaps containing active oxygen, the step which 60 consists in causing a peroxid salt of an alkali to act upon free fatty acid in the presence of heat.

In testimony whereof I have signed my name to this specification in the presence of 65 two subscribing witnesses.

RICHARD FRIEDRICH WOLFFENSTEIN.
